CALCULATING MACHINE

Karl Otto Reinhold Henzelmann, Glashutte,
GermanyApplication January 31, 1933, Serial No. 654,409
In Germany April 28, 1931

6 Claims. (Cl. 235—79)

My invention relates to calculating machines and is adaptable to machines of the type in which the multiplicand is set up on a key board and a crank is rotated in conformity with the multiplier and in which multiplicand slides and multiplier racks are employed. I provide, in combination with the key-board, which is subdivided into key frames, a locking and shifting lever or similar member for each key frame which lever 10 or member in one of its positions permits entrainment of the corresponding multiplicand slide, while in the other position it locks the entrained slides and at the same time operatively connects the keyboard to the racks of a multiplier control mechanism so that, upon the subsequent depression of a key, the multiplier racks are operated. In this manner it is possible to operate with a single keyboard on which the multiplicand and the multiplier are set up in succession.

Another advantage offered by the new machine is that corrections can be made during each setting-up without having to clear away all the characters already set up.

A special key which will be referred to as the "multiplier determining key" is provided for operating the locking and shifting lever of the individual key frames. When this key is depressed, it brings a mechanism to act on the locking and shifting levers by which these levers 20 which in their initial position permit operation of the multiplicand slides, are moved into their second position. In this position of these levers connection to the racks of the multiplier control mechanism is effected. The keys which have 30 been depressed, are locked in the usual manner and the multiplier determining key is operated whereby the keys are released after the multiplicand slides have been locked.

In the drawings affixed to this specification and 40 forming part thereof a machine embodying my invention is illustrated diagrammatically by way of example.

In the drawings

Fig. 1 is a plan view of the machine,

Fig. 2 is a section along the line II—II of Fig. 1, drawn to a larger scale and showing the position of the various operative elements of one of the key frames in their normal or starting position, the locking and shifting lever being in position permitting entrainment of the multiplicand slides,

Figs. 2a and 2b are perspective showings of the same elements shown in Fig. 2 with parts broken away for better illustration,

Fig. 3 is a view similar to that of Fig. 2 show-

ing one of the keys depressed and the multiplicand slide moved a corresponding distance to the left in the figure,

Fig. 4 is a similar view showing the position of parts just after movement of the locking and shifting lever into its second position and locking of the multiplicand slide,

Fig. 5 is a similar view showing the position of parts after release of the key locking bar and entrainment of the multiplier rack,

Fig. 6 is a similar view showing the position of parts after the depression of a key causing operation of the multiplier rack,

Fig. 7 is a showing of the multiplier determining key and related parts, in position permitting setting of the multiplicand,

Fig. 8 is a similar view of the multiplier determining key and related parts, in position for the setting of the multiplier,

Figs. 7a and 8a are details on an enlarged scale 20 showing the locking and shifting lever in its two operative positions, Fig. 8a showing the parts in multiplier setting position,

Figs. 9 and 10 are sections on the line IX—IX in Fig. 1, drawn to a larger scale and showing 25 two positions of a key which will be referred to as the "starting" key,

Figs. 11, 12 and 13 are sections on the line XI—XI in Fig. 1, drawn to a larger scale and showing three positions of a key which will be 30 referred to as the multiplicand determining key,

Fig. 14 is a perspective illustration of the driving mechanism of the machine, and

Fig. 15 is a detail of the multiplier control mechanism, drawn to a larger scale and taken 35 on the sectional plane II—II in Fig. 1.

Referring now to the drawings, and first to Fig. 1, A is the frame or body of the machine, with windows Md for observation of the multiplicand, and dial wheels 38 (Figs. 2 to 6) below 40 the windows Md. 51 is a side plate at the left, and 51' is the corresponding side plate at the right, of frame A. B is the multiplier control mechanism, with windows Mr and multiplier control wheels 68, as shown for instance, in Fig. 2 45 at the right and C is the carriage with windows T for the result and windows RC for the revolution counter in its top plate 18.

1 is the keyboard, with the usual keys 3. The keys are subdivided into nine key frames each 50 with a top plate 2, an inspection hole 4 in the plate, and nine keys 3.

The multiplier control mechanism, with its top plate 7 and the windows 8 in the top plate, is 55 arranged in front of the keyboard 1. Arranged

at convenient points on the keyboard are the usual operating keys.

Key frames

5 One of the key frames whose rectangular top plates 2 appear in Fig. 1, will now be described, it being understood that all nine key frames of the keyboard are exactly alike.

Referring first to Figs. 1 to 6, 21 are the bars of the nine keys 3 in the frame. Each key bar is guided in a hole of the top plate 2 at its upper end and at its lower end is equipped with a roller 23 engaging in a vertical slot of a guiding plate 22 which extends downwards from the top plate 2. 24 is a lower setting bar whose front end is supported by a link 25 which is fulcrumed on the plate 22 and whose rear end is supported by another link 26, also fulcrumed on the plate 22. This link is a bell crank whose longer arm 27 functions as a dog for controlling an upper setting bar 29. This upper bar which is mounted to slide below rail 22a of the guiding plate 22, is equipped with a pin 28 at its rear end and is under the action of a spring 160, 25 which is attached to the upper setting bar 29 at 161 and to the plate 22 at 162. The upper setting bar 29 is also equipped with a multiplier shift lever 31 which is fulcrumed on it at 30. The multiplier shift lever 31 is L-shaped, with 30 a long and substantially horizontal arm and a short and substantially vertical arm. The spring 160 causes the pin 28 to engage the longer arm 27 of the link 26 so as to return the setting bars 24, 29 to their initial positions.

35 64 is a pawl which is pivoted to the multiplier shift lever 31 near its front end at 63. 65 is a spring which connects the longer arm of the pawl 64 to the short vertical arm of the lever 31, so that the shorter arm of the pawl is held 40 against a pin 31' on the horizontal arm of the multiplier shift lever. 64' is a cam at the front end of the pawl 64 and 64'' is a slot at the rear end of the cam. 67 is a multiplier rack which is mounted to slide in the frame A, one 45 rack 67 being provided for each key frame in line with its pawl 64. Each rack has teeth 67' which engage in a pinion on the shaft of a multiplier control wheel forming part of the multiplier control mechanism B. The multiplier 50 wheels 68 are inspected through the windows 8 in the plate 1, as described with reference to Fig. 1. 66 is a pin at the rear end of the rack 67 which upon the return movement of the lever 31 and the pawl 64, under the action of the 55 spring 160 attached to the upper bar 29, bears on the cam 64' of the pawl, depressing the cam 64' and lifting the rear end of the pawl off the pin 31', as shown in Fig. 4, until finally the parts 60 assume the position illustrated in Fig. 5, the pawl 64 under the action of its spring 65 engaging the pin 66 on the rack 67 by its slot 64''.

Multiplicand slide

65 The multiplicand slide of the key frame will now be described with reference to Figs. 2a and 2b. The slide is a twisted flat bar with a vertical front portion and a horizontal rear portion, which is mounted below the top plate 2, and 35''' is an abutment for the front end of the slide whose 70 position below the top plate 2 is shown in Fig. 2. 48 is a hook on the slide 35 to which is connected a spring 39 which pulls the vertical front end of the slide into engagement with its abutment 35'''. At the front end the slide has a 75 rack 35'' with vertical teeth in the lower edge

of the slide. At its horizontal rear end it is equipped with a rack for meshing with a pinion 37 of multiplicand wheel 38 which is inspected through the window 4 in the top plate 2 (Fig. 2). 36' is a claw at the rear end of the slide which cooperates with the usual selector gear 36.

Locking and shifting lever

35' (Figs. 2a and 2b) is a fixed block on which a locking and shifting lever 33 is fulcrumed at 10 34. The locking and shifting lever 33 has a slot 33' for a pin 32 on the short vertical arm of the lever 31 to engage in. 42 (Fig. 2a) is a double-armed coupling lever, which is fulcrumed on to plate 355 of the slide 35 at 41 and 43 is 15 a spring on the slide 35 which engages the rear end of the double-armed lever 42. 44 is a pin at the front end of the double-armed coupling lever which, under the pressure of the spring 43, bears on the shouldered upper edge 33a (Fig. 20 2b) of the lever 33. Below the pin 44, the front end of the double-armed coupling lever 42 is equipped with a projection 42' which is adapted to engage a lug 29' on the upper setting bar 29.

45 (Fig. 2) is the usual serrated locking bar for holding depressed keys 3 in their depressed position. 47 is a spring catch which is fulcrumed in the key frame at 46 near the front end of the key frame, and 48 is a spring which engages the front end of the spring catch. 47' is a tooth at 30 30 the rear end of the spring catch which engages the teeth of the rack 35'' under the pressure of the spring 48. 47'' is a pin below the tooth 47' which engages in a vertical slot 35'' of the lever 33 (Fig. 2b). 35

Setting up multiplicand and multiplier

When one of the keys, for instance, the "5" key, Fig. 3, is depressed and arrested by the locking bar 45, its roller 23 bears on the upper edge 40 of the lower setting bar 24 and depresses this bar, rocking the link 25, 26 and the dog 27. The dog 27 moves the upper setting bar 29 to the rear by its pin 28. At the same time, the lug 29' of the upper bar 29 engages the projection 42' of the 45 double-armed coupling lever 42, so that the multiplicand slide 35 is moved to the rear by the cooperation of the lug and the double-armed coupling lever and shifts the selector gear 36 to the rear for a corresponding distance.

The multiplicand and the multiplier are set up by depressing the keys 3. In order to effect this it is necessary that the key 3 which has been depressed, as shown for the "5" key in Fig. 3, and has been locked by the bar 45, should be released 55 while maintaining the selector gear 36 in the position to which it has been moved by the depression of the key. The release of the depressed key is effected by the multiplier determining key 16 which will now be described with reference to 60 Figs. 7, 8, 9 and 10. The key 16 which, as shown in Fig. 1, is marked with the sign "mr", is secured at the upper end of a crooked bar 49. The bar is fulcrumed to the left side wall 51 of the casting A at 50, and positioned at the left or outer 65 side of the wall 51. 52 is a spring which is anchored on the wall 51 at 51' and holds the key bar 49 against a check 51''. 49' is a roller on the bar 49 of the key 16 which bears on an arm 53. This arm is secured on a shaft 54 which, as 70 shown in dotted lines in Fig. 1, extends transversely of the machine in front of its keyboard and is journaled in the side wall 51 at the left and in the corresponding side wall 51' at the right. 49'' is a downwardly extending projection 75

at the rear end of the bar 49 which bears on a pin 55. This pin which projects through a slot in the left side walls 51, is secured on a double-armed lever 57 which is fulcrumed on the inner side of the side wall 51 at 56. The upper end of the double-armed lever has a pin 57' which engages in the slotted front end of a connecting rod 58, with a pull back spring 58', whose rear end is fulcrumed to a rocking lever 59 at 59'. The rocking lever 59 is mounted on a shaft 60 which extends in parallel to the shaft 54 at the rear of the keyboard and is journaled in the two side walls at its ends, its position being shown in dotted lines in Fig. 1.

15 By depressing the multiplier determining key 16, it is moved from the position shown in dotted lines in Fig. 8 into the position shown in full lines, against its pull-back spring 52. The shafts 54 and 60 are rotated clockwise in their bearings upon the depression of the key 16, through the mechanism which has been described. The shaft 54 is equipped with a radial pin 61 for each key frame. Each pin is adapted to engage a hole in an extension 35''' at the front end of the corresponding locking and shifting lever 33, as best seen in Fig. 2b. Similar pins 62 are provided on the shaft 60 which extends in parallel to the shaft 54 at the rear of the keyboard. Each pin 62 is adapted to cooperate with the corresponding locking bar 45, as best seen in Fig. 3. When the shafts 54 and 60 are rotated clockwise by depressing the key 16, Fig. 8, the locking and shifting levers 33 of all keyboards are raised by the pins 61 on the shaft 54 engaging in the holes of their extensions 35''' and at the same time the locking bars 45 are moved in forward direction by the pins 62 on the shaft 60. The locking bar 45 now releases the "5" key which had been depressed so that the key returns into its initial position. The pin 47' at the rear end of the spring catch 47 (Fig. 2b) serves for holding the multiplicand slide 35 and its selector gear 36 in the position to which they had been moved by the depression of the "5" key. The pin 47', as described, projects into the vertical slot 33''' of the locking and shifting lever 33. The locking and shifting levers 33 are held in raised position by locking the shaft 54, as will be described below with reference to Figs. 11, 12 and 13. When the levers 33 have been raised by the pins 61, as shown in Fig. 5, the lower end of each vertical slot 33''' engages the corresponding pin 47' and holds the tooth 47' at the rear end of the catch 47 engaged with the rack 35''' at the front end of each multiplicand slide.

55 Those multiplicand slides 35 which have been moved to the rear in the individual key frames by depression of a key, such as the "5" key, are now locked, and so are their selector gears 36. As mentioned, the "5" key which had been depressed, is released by the locking bar 45 and returns to its initial position. In this manner, operation of the key 16 causes the keys 3 to return to their initial positions so that the keyboard is cleared.

60 Those multiplicand slides 35 which have been retained by the corresponding teeth 47' in the individual frames remain locked for the present while the springs 160 (Fig. 2) through the medium of the pins 28 on the upper setting bars 29 return the upper and lower bars 29 and 24, together with their links 25 and 26, 27 into initial position. The coupling levers 42 on the multiplicand slides 35 are raised by the raising of the levers 33 to which they are connected by their pins 44, so that the projections 42' on

the coupling levers 42 move clear of the lugs 29' on the upper bar 29 and the lugs do not interfere with the multiplicand slides 35 when the multiplier is set up, as will be described below.

In my machine, the multiplicand and the multiplier are set up by means of a single set of keys, and therefore it is necessary that the keys should be alternately connected to the means for setting up the multiplicand and to the means for setting up the multiplier. The means for setting up the multiplicand include the multiplicand slides 35, and the means for setting up the multiplier include the racks 67.

Referring now to Figs. 7a and 8a, Fig. 7a shows the initial positions of the multiplier shift lever 31 and the locking and shifting lever 33. This position of the levers corresponds to the initial, i. e. undepressed, position of the multiplier determining key 16. The levers 31 and 33 are both in their lowermost position, the projection 42' on the coupling lever 42 is in cooperative relation with respect to the lug 29' on the upper setting bar 29 and the bar 29 entrains the multiplicand slide 35 through the medium of the lug 29' and the coupling lever 42. This permits setting up the multiplicand by depression of keys 3. The multiplier shift lever 31 is also in its lowermost position so that the slot 64''' in the pawl 64 clears the pin 66 on the rack 67. When, on the other hand, the key 16 is depressed as shown in Fig. 8, the multiplier lever 31 and the locking and shifting lever 33 are raised together as shown in Fig. 8a, and the projection 42' of the coupling lever 42 is moved clear of the lug 29' on the upper bar 29 so that the multiplicand slide 35 is not entrained. At the same time, the pawl 64 on the lever 31 engages the pin 66 on the rack 67. In this position of the key 16, the multiplier can be set up.

The means for locking the shaft 54 in the position in which the levers 31 and 33 are raised for setting up the multiplier after the key 16 has been depressed, as shown in Figs. 8 and 8a, will now be described with reference to Figs. 11, 12 and 13. 92 is a lever on the shaft 54 whose position in the frame A is indicated in dotted lines at the right in Fig. 1. 92' is a pin at the free end of the locking arm 92 which is adapted to be engaged by a shoulder 93' on a pawl 93. The pawl 93 is equipped with a pull-back spring 93''' and is mounted to rock about a pin 94 so that the shaft 54 is held in position against the action of the spring 53' at the end of the arm 53, Figs. 7 and 8.

When, while the shaft 54 is locked against rotation in the manner described, the multiplier is set up by depressing the corresponding keys 3, as shown for the "3" key in Fig. 6, the keys in the several key frames operate the corresponding lower bars 24 and the multiplier racks 67 in the manner described, while the multiplicand slides 35 and the parts connected to them are not influenced, being retained by the catches 47 engaging racks 35''. The locking and shifting levers 33 are held in their raised position, as best seen in Figs. 8a, and being raised, connect the pawls 64 to the pins 66 on the racks 67 so that upon the depression of a key 3 the corresponding multiplier wheel 68 in the multiplier control mechanism B is rotated and displays the numeral of the key in its inspection window 8. Upon depression of the "3" key as in Fig. 6, the numeral "3" will appear in that inspection window which is allotted to the key frame where the key has been depressed.

The multiplication is now performed by starting the machine through the medium of the starting key 17, which is marked with the sign S.

Operation of multiplier control mechanism

Referring now to Figs. 9 and 10, the horse-shoe shaped bar 69 of the starting key 17 is fulcrumed on the inner side of the left side wall 51 at 78. 86 is a spring which holds the 10 key bar against a check 87. 71 is a dog on the bar 69 of the starting key 17 which is adapted to be engaged by a notch 72' in a lever 72. The lever 72 is fulcrumed on the side wall 51 at 73 and is equipped with a spring 74 which tends to 15 pull it in forward direction. 75 is a pin on the lever 72 which engages in a slot 76' of a link 76. The other end of the link is pivoted to a lever 77 on a shaft 78 which extends along the 20 multiplier control mechanism B in front of the multiplier wheels 68 and in parallel to the shaft 54. The position of the shaft 78 is best seen in Fig. 14. The same shaft 78 supports a feeler 79 for each multiplier wheel. 80 is a locking plate 25 on each multiplier wheel, with a recess 80'. The feelers 79 are equipped with pins 79' for cooperation with the locking plate 80. The feelers 79 are operated by conventional means which form no part of the present invention. For example, they may be controlled by cams 163 (Figs. 30 9 and 10) on a shaft 120 which forms part of the driving mechanism of the machine and will be described below. The cams 163, which rotate in the direction of the arrow Fig. 9 with the shaft 120, cooperate with cam levers 164 which 35 operate the feelers 79 and are held against the corresponding cam 163 by springs 165. The rotation of the shaft 120 is so timed with respect to that of the driving shaft of the machine, (as will be described below) that the feelers 79 are 40 released and moved toward the corresponding locking plate in the direction of the arrow in Fig. 9 under the action of their springs 165 once per revolution of the driving shaft. Fig. 10 shows, in dotted lines, a feeler 79 in the position 45 in which its pin 79' engages in a recess 80' of the locking plate.

82 is a shaft, Figs. 9 and 10, which is mounted in parallel to and at the rear of the shaft 78. 81 is a lever on the shaft which bears against the 50 lower edge of the key bar 69 of starting key 17 with a roller 81' at its free end. A link 83 is pivoted to the upper end of lever 81 at 81'' and is equipped with a spring 84 which pulls the link to the left so as to hold the roller 81' against the 55 lower edge of the key bar 69. When the starting key 17 is depressed the lower edge of the key bar 69 forces the roller 81' and lever 81 to the right as shown in Fig. 10. This also pulls link 83 to the right. The other end of link 83 is connected 60 to a device for cutting in a motor (not shown) which starts rotation of shaft 132. This motor starting device may be similar to that shown in German Patent No. 457,825, Fig. 2, for example. 65 69' is a cam on the key bar 69, of the starting key 17. The cam bears on the double-armed lever 81 which has already been described with reference to Figs. 7 and 8. While the multiplier determining key 16 clears the multiplicand set up 70 in the manner described above, the starting key 17 clears the multiplier set up. 85 is a link which is pivoted to the lower end of the lever at 81''. The link 85 is operatively connected to a mechanism for feeding the carriage of the machine 75 by connecting it to the drive shaft 132. This

mechanism may be similar to that described in German Patent No. 492,236, for example, and has not been shown since it does not constitute part of the present invention. 88 (Fig. 9) is a pin on that portion of the key bar 69 which extends upwardly beyond its fulcrum 78 and 89 is a pin on the shaft 54 which is adapted to cooperate with the pin 88 on the key bar. When the multiplier determining key 16, whose bar is operatively connected to the shaft 54 by the means described, is 10 in its undepressed position, the pin 89 is in its lowermost position as indicated in dotted lines in Fig. 9 so that the starting key 17 is locked against operation, while the key 16 is not depressed. This prevents untimely operation of the 15 two keys 16 and 17 which, as shown in Fig. 1, are arranged side by side and might be confused by the operator. When the key 16 has been depressed as shown in full lines in Fig. 8, the shaft 54 is rotated and the pin 89 is moved into the 20 full-lines position shown in Figs. 9 and 10 so that the starting key 17 is now free to be operated. The starting key, by the cam 69' (Figs. 9 and 10) on its key bar 69, acts on the double-armed lever 57 in the same manner as the multiplier determining key 16 acts through its projection 49''. This action rotates shaft 68 in a clockwise direction through a small angle (Fig. 8) which results in releasing the keys which have been depressed for setting up the multiplier. 25

110, Fig. 14, is a rack on the carriage C which meshes with a pinion 111 on a shaft 112. This shaft 112 extends in the longitudinal direction of the machine in parallel to its left side wall 51. The ends of the shaft 112 are supported in suitable bearings (not shown). 113 is a bevel pinion on the front end of the carriage shaft 112, 114 is a bevel pinion on a vertical shaft 115 which meshes with the bevel pinion 113 on the carriage shaft, and 116 is a sprocket at the lower end of 40 the vertical shaft 115, shown in Figs. 14 and 15. 118 (Fig. 14) is a corresponding sprocket at the right of the machine and 117 is a chain traveling on the sprockets which is secured to an extension 123' (Fig. 15) of a bridge 123 forming part of 45 the multiplier control mechanism as will be described below. The bridge 123 is mounted to slide along the cam shaft 120, (Fig. 15) and a shaft 119 which extends in parallel relation to the cam shaft. Both shafts, which are splined, 50 extend also in parallel relation to the shaft 78 on which the feelers 79 are mounted. One of the feelers is shown in Fig. 14.

When the carriage 18 moves, the shaft 112 is rotated through the rack 110 and the pinion 11, 55 and by its rotation the bridge 123 is moved along the shafts 119, 120 through the medium of bevel gearing 113, 114, shaft 115, sprockets 116, 118 and chain 117. By this means the relative positions of the carriage 18 and the bridge 123 are 60 maintained fixed. 121 is a sleeve which engages in the spline of the shaft 119 with a tongue 119' and 122 is a sleeve which engages in the spline of the shaft 120 with a tongue 120'. The two sleeves move with the bridge 123 as it slides along 65 the shafts 119 and 120. The bridge is divided and its lower portion is equipped with the extension 123'. The sleeve 121 on the shaft 119 is equipped with an arm 121', with a roller 124 at its free end, and 122' is a tooth or cam on the sleeve 70 122 which is adapted to engage in the star wheels 125 of the dial wheels 68.

Multiplier drive

128 (Fig. 14) is a shaft which extends in paral- 75

16 to the left side wall 51, 127 is a pair of bevel gears which connect the shafts 126 and 128, and 129 is a clutch of any suitable type on the front end of the shaft 128, with a bell-crank 90 for 10 operating it, by which the shaft can be connected to a bevel pinion 130 which is normally free to rotate on the shaft and meshes with a bevel pinion 131 on the shaft 120 on which the sleeve 122 is splined. Clutch 129 may be designed, if desired, 0 in a manner similar to the clutch shown in German Patent No. 457,825, Figs. 7 and 8, the bell-crank 90 of my Fig. 14 performing the same 5 function as the element 21 of the German patent. 133 is a cam on the driving shaft 132, (Fig. 14) and 134 is a rocking lever which is fulcrumed in the frame of the machine at 135 and is equipped with a pull-back spring 136. 134' is a pin at the upper end of the rocking lever 134 which is operated by the cam 133 so that the lever 134 is 10 rocked once for each revolution of the driving shaft 132. 137 is a link which is pivoted to the rocking lever 134 at 134' and is supported on the slotted guide 138. 139 is a pin on the bar 69 of the starting key 17 (Fig. 14) which is adapted to 15 cooperate with the shorter arm of a double-armed lever 140 fulcrumed at 140' on side wall 51. The longer arm of the lever engages below a pin 141 on the link 137. 137' is a notch in the link 137 which engages a pin 142 on a plate 143 when the longer 20 arm of the lever 140 raises the link 137. The plate 143 which is supported by a pin 146 has a slot 143' at its lower end and is connected to a spring 146' which pulls the lower end of the plate 143 in forward direction until the end of the slot 25 143' bears on a pin 146. 144 is a connecting rod by which the pin 143' on the upper end of the plate 143 is connected to a crank 145 on the splined shaft 119 which bears the sleeve 121, Fig. 15.

40 147 is a second pin on the lower end of the plate 143 which is engaged by a cam 148 on the shaft 149 by which the feed of the carriage C is released upon rocking of the lower part of plate 143. The means by which this is effected do not 45 form part of the present invention and are not illustrated.

50 150, Fig. 15, are double-armed levers, one for each dial wheel 68, which are fulcrumed at 151 and are each equipped with a spring 152 holding 55 it against a check 153. The lower end of each lever 150 projects into the path of the roller 124 on the sleeve 121. The upper end of each lever cooperates with a lug 154 at the side of the corresponding plate 80. The lugs 154 are so positioned 60 that they face the end of the lever 150 when the recess 80' of the locking plate is in position to be engaged by the pin 79' on the feeler 79. In this position of the dial wheel, the numeral "0" appears in the corresponding inspection 65 opening 8.

Operation of machine.

70 When the starting key 17 is depressed as shown in Fig. 10, it is held down by the lever 12 engaging the dog 71 on the bar 69 with its notch 72'. The double-armed lever 57 has been rocked about its fulcrum 56 by the cam 69' and the link 58, through the medium of the lever 59, the shaft 60 and the pin 62, clears the multiplier from the keyboard. At the same time, the link 85 operates 75 upon a carriage reversing means (not shown) in such manner that the carriage is moved to the right, corresponding to multiplication. Upon depression of the starting key the rod 83 is pulled to the right in Fig. 9, by the action of roller 81'

and lever 81. Rod 83, through mechanism which may be similar to that shown in German Patent No. 457,825, Fig. 2, cuts in the motor and starts rotation of shaft 132.

The bellcrank lever 90 of clutch 129, Fig. 14, is 5 fulcrumed to the frame of the machine, its horizontal arm extending into operative relation to a recess 69'' in bar 69, as shown in Figs. 9 and 10. The vertical arm of the bellcrank lever controls the clutch 129 by which the bevel pinion 130 is 10 connected to the shaft 128. Depression of the starting key 17 causes the bellcrank lever 90 to throw in the clutch 129 and to operatively connect the pinion 130 to the shaft 126 to which the shaft 128 is permanently connected by the bevel 15 pinions 121. When the shaft 126 is rotated this, in turn, rotates the shaft 120. Once per revolution of the shaft 120 the tooth 122' (Fig. 15) of its sleeve 122 engages in the star wheel 125 of the corresponding dial wheel 68, turning the dial 20 wheel back one digit per tooth. This is repeated until the numeral "0" appears in the inspection hole 8. In this position, as shown in Fig. 15, the lug 154 is opposite the upper end of the double-25 armed lever 150.

Depression of the starting key 17, (Figs. 9, 10 and 14) causes, through the medium of the pin 139, (Fig. 14) the double-armed lever 140 and the pin 141 on the link 137, the link to be connected to the plate 143 by the recess 137' in the link engaging the pin 142 on the plate 143. The reciprocating movement imparted to the link 137 causes the plate 143 to rock about the pin 146 in its slot 143' once for each revolution of the driving shaft 132. The rocking movement is transmitted to the shaft 119 through pin 143', connecting rod 144 and crank 145. The consequence is that the upper end of the lever 150 (Fig. 15) is moved in forward direction, through the medium of the roller 124 on the arm 121' of the sleeve 121, 40 which moves in the direction of the arrow in Fig. 15. The lever 150 is free to perform its rocking movement against the action of spring 152 unless the lug 154 is opposite the upper end of the lever corresponding to the zero position illustrated in Fig. 15. In the latter event the motion described is blocked and the pin 143' (Fig. 14) on the plate 143 then becomes a fixed pivot about which the plate is rocked by the link 137 against the action of its spring 146', this being permitted 45 by the slot 143' in the lower end of the plate 143. The rocking movement of the plate about the pin 143' is transmitted to the cam 148 (Fig. 14) on the shaft 149 by the pin 147. The shaft 149, through means not shown, now connects the carriage-feeding means to the driving shaft 132 while at 50 the same time the shaft 126 is disconnected from the driving shaft 132. The carriage is now fed to the right for a single order. Obviously, the shaft 128 (Fig. 14) and the shaft 120 to which 55 it is connected by the bevel pinion 130, 131, are also arrested during the feeding movement of the carriage.

The carriage, through rack 110, (Fig. 14) pinion 11, shaft 112, bevel pinions 113, 114 and shaft 65 115, is connected to the sprocket 116 on which the chain 117 is carried as described above so that the chain 117 and the bridge 123 are fed through a corresponding distance during the feeding movement of the carriage. Consequently the 70 sleeve 121 and 122 are shifted a single order, in relation to multiplier wheels 68, for each single order shift of the carriage, and the members 124 and 122' (Fig. 15) of the sleeves 121 and 122 are placed in active relation with respect to the cor- 75

- responding members of the next following multiplier wheel 68. The star wheel 125 of this next dial wheel is now rotated by the tooth 122' unless the parts are blocked by the lug 154 in the zero position of the dial wheel. At the same time, the feelers 78 are rocked in the direction of the arrow, Fig. 9, once per revolution of the driving shaft 132, and if all dial wheels 68 are in zero position, with "0" appearing in the inspection holes 8, 10 and the pins 78' at the free ends of the feelers are opposite to the recesses 80' and are free to move to the rear into the position shown in dotted lines in Fig. 10. When all the dial wheels are in zero position the arm 79 which is secured on the 15 shaft 78 of the feelers, moves the link 76 to the rear and pushes the lever 72 away from the dog 71 on the key bar 68, (as shown in dotted lines in Fig. 10). It is thus seen that, during operation of the machine, when the carriage is being moved, 20 the bridge 123 (Fig. 14) is also moving and at this time the sleeve 122 (Fig. 15) with tooth 122' is idle. But when the carriage stops to conduct a transfer operation, the bridge 123 is stopped beneath one of the multiplier wheels 68 and the 25 sleeve 122 with its tooth 122' rotates, being driven through gears 130, 131, clutch 128, shaft 128, gears 127 and shaft 126.
- Obviously the length of the slot 78' (Fig. 9) in the link 76 must be so determined that the bar 30 catch 72' is not operated during the normal operation of the feelers 78. Only when recesses 80' are opposite the pins 78' at the free end of the feelers 78, the bar catch 72 is pushed back by the means 76.
- 35 The key bar is now released and the key 17 is returned to its initial position, Fig. 9, by the spring 86. This causes the motor-switching rod 83, and the bell-crank lever 88, Fig. 14, to return into their initial positions, so that the machine is 40 now arrested. Obviously, the lever 87, (Fig. 9) with the links 88 and 85 which are connected to it, also returns into its initial position. The multiplication is now completed and the result is read in the usual manner in the windows T.
- 45 If it is desired to clear the multiplier from the keyboard before the machine is started by depressing the key 17, the multiplicand determining key 18 at the right of the machine is operated, see Figs. 11, 12 and 13. This key is marked *md* in Fig. 1. The key bar 85 of key 18, Figs. 11, 12 and 13, is fulcrumed about a pin 86 and is held against a check 88 by a spring 87. 100 is a pawl which is fulcrumed to the key bar 85 at 88, and 101 is a 50 spring which tends to rotate the pawl 100 anti-clockwise. In the position illustrated in Fig. 11, the pointed end 100' of the pawl 100 is depressed by the pin 82' at the free end of the locking lever 82 on the shaft 54.
- 55 60 85' (Figs. 11, 12 and 13) is a pin on a downward extension of the key bar 85 which engages in the slotted front end 102' of a link 102 whose rear end is pivotally connected at 103' to a lever 103 on the shaft 60.
- 65 60 By depressing the multiplier determining key 18, (Figs. 7 and 8) the lever 82 on the shaft 54 and the pawl 83 move in the positions illustrated in Fig. 12, as described above. At the same time the pointed end 100' of the pawl 100 engages a dog 93" on the pawl 83. When the multiplicand determining key 18 is depressed into the position shown in full lines in Fig. 13, the pin 15' on the downward extension of the bar 85 pulls the link 102 to the rear and the shaft 60 is rotated in 70 the manner described, causing its pins to operate
- 75

the locking bars 45 (Fig. 2) and to release all keys 3 of the keyboard, permitting them to return into their initial positions. When the key 18 is depressed, the hook 100' of the pawl 100 engages behind the dog 93". When the key is released, the bar 85, under the action of its spring 87, returns into its initial position and entrains the pawl 83 through the medium of the pawl 100, rocking it to the rear. In this manner, the shoulder 83' which supports the pin 82' at the end of the lever 16 82 on the shaft 54, is withdrawn, permitting the lever 82 to return into the position illustrated in Fig. 11. The pawl 100 is engaged at its hook 100' and the pin 82' and moved into the position illustrated in Fig. 11. At the same time the pins 81 14 on the shaft 54 move into the position illustrated in Fig. 2 and the settinglever 33 moves into the corresponding position, as described. In this position of the parts the machine is in its starting position ready for the setting up of a multiplicand. 20

Example of multiplication

The operation of the machine will be best understood from the following example:

Multiply "56" by "348". Set up the multiplicand by depressing the "6" key 3 in the key frame at the right-hand end of the keyboard, and the "5" key 3 in the frame at the left of this frame. Depression of the keys, through the means described, in connection with Figs. 2, 2a 30 and 2b, i. e., lower bar 24, dog 27, upper bar 29, lug 29' and double-armed coupling lever 42, causes the multiplicand slides 35 in the two key frames to be shifted and the selector gears 36 to be adjusted. The characters "5" and "6" of the 35 multiplicand 56 now appear in the inspection windows Md of the two key frames.

The multiplier determining key 18 (Fig. 9) is now depressed. This causes partial rotation of the shaft 54 in the manner described, and raising of the locking and shifting levers 33 (Fig. 2b) in all key frames. Raising of these levers permits the catches 47 to lock the slides 35 as the pin 47" are set free by the slots 33" of the setting levers. The teeth 47' of the catches 47 now 45 retain the slides 35 which have been displaced, by engaging in their racks 35". At the same time, through the medium of the link 58 (Fig. 7) and the shaft 60, with its pins 62, the keys which have been depressed, are released by the locking bars 45 (Fig. 2) clearing the keyboard but not influencing the multiplicand slides 35 which are locked by the catches 47 in the manner described against the pull of the springs 89. The keys which have been depressed, return to their initial positions while the setting wheels 36 of the first two key frames from the right remain in the positions to which they have been moved by the depressed keys. 55

The multiplier shift levers 31 have been raised 60 at the same time as the locking and shifting levers 33. The pawls 64 (Fig. 7a) on the levers 31 are raised with the levers so that upon the return of the bar 29 to the right the slots 64" move into reach of the pins 66 on the racks 67. 65 When the upper bars 29 of the two frames where keys have been depressed, return, the cams 64' of their pawls 64 engage below the pins 66 whereupon finally the pawls are connected to the 70 racks 67.

The upper bars 29 of the two key frames in which keys have been operated, are now connected to the racks 67.

The multiplier "348" is now set up on the key- 75

board by means of the keys 3. The upper bar 29 in the key frame at the right-hand end of the keyboard displaces the corresponding rack 67 until the character "8" appears in the inspection opening 8 of this keyboard, and similarly the upper bars 29 of the next two key frames operate their racks 67 to show "3" and "4" in the inspection windows 8. The starting key 17 (Fig. 9) is now operated to start the machine, as described. Depression of the starting key causes its recess 69" to operate the bell-crank 90 (Fig. 14) which in turn throws in the clutch 129. The cam 69' on the bar 69 operates the double-armed lever 57 and, through the link 58 and the shaft 60, clears the multiplier set up. The clutch 129 connects the shaft 126 to the shaft 120 (Fig. 15) with the sleeve 122 having the tooth 122'. By means of the rod 83, the motor is started and the shaft 120 rotates. The tooth 122' first cooperates with the star wheel 125 at the extreme right. The dial wheel 68 of this star wheel is at "8" and so the shaft 120 must perform eight revolutions until the lug 154 (Fig. 15) is in line with the double-armed lever 150 and "0" appears in the inspection opening 8. The multiplicand 56 has now been multiplied by eight and the numeral 448 is read in the windows T. The double-armed lever 150 is now prevented from moving by the lug 154 and the drive acts on the carriage feed, as described. After the carriage has been shifted one order to the right the tooth 122' has moved into line with the second star wheel 125 whose dial wheel 68 is at "4". The operation is now repeated, the shaft 120 performing four revolutions until the corresponding lug 154 has blocked the double-armed lever 150. The numeral 56 is thus multiplied by forty. The consequence is that "2240" is added to "448" and "2688" is read at T. At the same time, the carriage C has been shifted another order moving the tooth 122' in line with the third star wheel 125 whose dial wheel shows "3". After three revolutions of the shaft 120 the last dial wheel is at "0". This means that the numeral "56" has further been multiplied by three hundred so that

"16800" is added to the numeral in the windows T, making the result "19488".

As all dial wheels 68 are now at "0", all feelers 79 engage in the recesses 80' of the locking plate 80 by which means the machine is arrested in 5 the manner described.

I wish it to be understood that I do not desire to be limited to the exact details of construction shown and described for obvious modifications will occur to the person skilled in the art. 10

I claim:

1. In a calculating machine, in combination, a keyboard with keys capable of being set, setting means differentially actuatable by said keys, multiplicand slides, multiplier racks and a locking 15 and shifting means capable of being set in two positions; said locking and shifting means being adapted, when in one position, to cause entrainment of said multiplicand slides by said setting means and when in the other position being 20 adapted to lock said multiplicand slides and to operatively connect said multiplier racks to said setting means.

2. The device of claim 1 wherein a key is provided for operating said locking and shifting 25 means.

3. The device of claim 1 wherein said locking and shifting means comprises a pivoted lever.

4. In a calculating machine, in combination, a keyboard with keys capable of being set, multiplicand slides and multiplier racks, setting means differentially actuatable by said keys and shifting means capable of being set in two positions for operatively and selectively connecting said setting means either to said multiplicand slides or 35 to said multiplier racks.

5. The apparatus of claim 4 wherein said shifting means comprises slidable bars with stops for entraining said multiplicand slides and pawls for engaging said multiplier racks. 40

6. The apparatus of claim 4 wherein means are mounted on said shifting means for locking said multiplicand slides when said shifting means is in one of said two positions.

KARL OTTO REINHOLD HENZELMANN. 45
